FELLING MACHINE COMPANY, OF BOSTON, MASSACHUSETTS, A CORPORATION
OF MAINE.

FEEDING MECHANISM FOR BLINDSTITCH SEWING-MACHINES.

1,294,660.

Specification of Letters Patent. Patented Feb. 18, 1919.

Original application filed August 14, 1913, Serial No. 784,687. Divided and this application filed January 20, 1915. Serial No. 3,404.

To all whom it may concern:

Be it known that I, THOMAS J. HAYES, a citizen of the United States, and resident of Roslindale, county of Suffolk, State of Massachusetts, have invented an Improvement in Feeding Mechanism for Blindstitch Sewing-Machines, of which the following description, in connection with the accompanying drawing, is a specification, like characters on the drawing representing like parts.

This invention relates to improvements in feeding mechanism for sewing machines and is disclosed herein as applied to a blind stitch sewing machine for felling of the type illustrated in my Patent No. 1,230,159, granted to me June 19, 1917, of which this application constitutes a division.

In stitching garments and particularly in felling a superimposed layer of material to the base layer by blind stitching it is frequently necessary to cross thick seams and in so doing the material is often retarded so that stitches of unequal length are formed as the seam passes the stitch forming mechanism. One of the objects of this invention is to obviate this defect by providing a feeding mechanism in which the feed dog is independently yieldable at each end so that the dog is permitted automatically to accommodate itself to any unevenness in thickness of the material and also to provide means whereby the dog will ride easily upon the seam, engaging not only the seam but portions of the other surfaces of the material so that the material will be advanced uniformly notwithstanding the variation in thickness of the goods which passes the stitch forming mechanism.

Another object of the invention is to provide independently adjustable means for supporting the ends of the feed dog so that a greater or less pressure may be applied to the toe or the heel of the feed dog as may be desired.

Another object of the invention is to simplify the mechanism which actuates the feed dog permitting the same to be placed in a smaller space beneath the body portion of the machine and thereby allowing greater space for the introduction of the bender mechanism or other mechanisms

used in connection with the stitch forming mechanism.

Another object of the invention is to provide means easily accessible to the operator for adjusting the length of throw of the feed dog.

Other objects of the invention will more fully appear from the following description and drawings and will be pointed out in the annexed claims.

The drawings illustrate the invention as applied to a blind-stitch sewing machine for felling in which the stitch forming mechanism is located above the plane of the work support.

In the drawings:

Figure 1 is a side elevation partially in vertical section of a sewing machine embodying this invention.

Fig. 2 is a front elevation of the same,

Fig. 3 is a vertical transverse sectional view through the sewing machine arm and base plate showing the means for adjusting the feeding mechanism,

Fig. 4 is a detail plan view of the feeding mechanism, the work supporting plate of the work support being removed to disclose more clearly the operating mechanisms, and

Fig. 5 is a detail rear elevation of the same showing the shaft and sleeve for actuating the feeding mechanism, in section.

Fig. 6 is a detail view of the rock shaft connecting the work support and feed bar.

The sewing machine illustrated in the drawings comprises the usual base plate 1 having a standard 2 rising therefrom and supporting the overhanging arm 3, which terminates in a head 4 which supports the stitch forming mechanism.

The stitch forming mechanism disclosed herein comprises a curved oscillating needle carried by a needle bar 5 which is pivotally mounted upon a transverse shaft 6 in suitable bearings in a bifurcated bracket 7 which desirably is supported by a stem or stud 8 extending into the lower portion of the head 4. The bracket 7 may be secured to an oscillating or reciprocating member adapted to be vibrated laterally so that the needle may be presented in alternate thrusts in different planes or if desired may be permanently secured in the head to cause the

needle to reciprocate constantly in a single plane. In the particular machine illustrated herein the needle is arranged to oscillate in a plane inclined to the work supporting surface of the work support but it is to be understood that this is not of importance in connection with the present invention.

The head 4 is provided with a downward extension which supports a rotating hook 10 or other complementary stitch forming mechanism which may be actuated through a shaft 11 and suitable gears 12, 13 connecting the same to a gear 14 upon the main shaft.

The lower end of the extension 9 is provided with a preferably rigid presser foot 15 against which the work is held by a yieldable work support 16. The work support 16 is preferably in the form of a substantially rectangular plate carried upon the forked upper ends 17, 18 of a standard 19 which is journaled in suitable bearings in a web or bracket 20 depending from the under surface of the bed plate 1. The standard 19 is provided with a shoulder preferably in the form of a collar 21 which rests upon the upper end of a helical spring 22 surrounding said stem 19 and seated upon the end of the bearing in which said stem is journaled.

In order to provide for the feeding of the material between the work support and the presser foot, means are provided connecting the feed dog and the work support which will cause the feed dog to be lowered when the work support engages the material during the stitch forming operation and which will cause the feed dog to engage the material and the work support simultaneously to be released therefrom as the feed dog begins to move forward to advance the material beneath the presser foot. As illustrated herein the feed dog comprises the usual L-shaped cloth engaging portion 23 secured by suitable screws 24 to a feed bar 25 thus making a construction in which the feed bar and feed dog are practically integral. The term "feed dog" will be used hereinafter to designate this integral member in order to simplify the description of the operation of the mechanism which advances the work. The feed dog 25 is provided with a longitudinally extending recess 26 adapted to receive the end of a cylindrical pin or stud 27 which is supported upon an arm 28 extending laterally from a rock shaft 29, which is journaled in a bearing 30 in the upper portion of the standard 19, the opposite end of the rock shaft having an arm 31 which is pivotally connected at its end to a link 32 adapted to be reciprocated from a suitable driving shaft which will hereinafter be described. The reciprocation of the link 32 will cause the oscillation

of the rock shaft and will cause the same to raise and lower the feed dog and work support alternately in respect to the presser foot.

It will be noted that the pin 27 is arranged to move freely longitudinally in the slot 26 and constitutes a pivotal support which effects a raising and lowering of the feed dog.

In order to so support the dog that it may have a rocking movement which will permit it to ride up over seams and to accommodate itself to various differences in thickness of the material the ends of the dog are pivotally supported upon yieldable members. These may be independently adjusted so that a greater or less degree of pressure may be maintained upon the toe or upon the heel of the dog as may be desired. In the construction illustrated herein this is accomplished by providing extensions 33-34 which desirably extend laterally and downwardly and are pivotally secured at their lower edges respectively to links 35, 36 the lower ends of which links are pivotally connected to pins 37-38 which desirably are slidably mounted in bosses 39 and 40 integral with the depending web or bracket 20.

The bosses are countersunk to provide seats for helical springs 41 which desirably engage at their upper ends shoulders or collars 42 upon said pins 37-38, the lower end of the springs 41 being seated in the recesses 43 of milled nuts 44-45 which are screwed into the lower end of the countersunk portion of the boss 39-40. It will be obvious that by adjusting the milled nuts 44-45 the tension upon the springs which support the pins 37-38 may be independently adjusted and the toe or the heel of the dog caused to engage the material with the amount of pressure desired.

The extensions 33-34 of the dog are desirably provided with slots 46-47 to receive members of pivotal guiding arms 48-49. As illustrated herein the arm 48 is pivotally secured to a stud 50 extending from the bracket 20. The arm 49 is in the form of a yoke having a shaft 51 engaged by the bifurcated end of an extension 33 of the feed bar, the extension 33 being thus bifurcated to form a rigid construction which will prevent lateral tilting of the feed bar and feed dog. The arm 49 may be supported from the rock shaft 52 which serves to transmit longitudinal movement to the feed dog by arms 53 extending upwardly therefrom and form journals for a short shaft or stud 54 upon which the arm 49 may be pivotally hung.

Backward and forward or feeding movement is transmitted to the feed dog from the rock shaft 52 through the arms 53, the extended end of the shaft which is carried

thereby being pivotally attached to the end of a link 55 which is pivotally secured at its opposite end to a stud or screw 56 secured to the upper portion of the extension 5 34 of the feed dog.

It will be obvious that as the link 55 is reciprocated by the rock shaft 52 the feed dog will be moved forward and backward and that by so timing the reciprocation of the link 32 which actuates the rock shaft 29 the feed dog may be given the usual four motion feed.

It will be noted that when the feed dog is retracted it will be depressed by the arm 28 of the rock shaft 29 so that the cloth engaging portion 23 thereof will be beneath the surface of the work support. When the feed dog is about to be advanced it will be raised to its highest limit extending above the surface of the work support and engaging the cloth.

At the same time the actuation of the rock shaft 29 will serve to depress the work support so that the cloth will be free to move along the presser foot as the feed dog is advanced.

In order to provide a maximum amount of room beneath the bed plate of the machine for the bender mechanism and other operative parts and also to simplify the construction of the machine I have supported the shafts for operating the feeding mechanism from a single series of bearings and inclosed the shaft for advancing and retracting the dog within a sleeve shaft which is operatively connected to the mechanism for raising and lowering the feed dog.

As illustrated herein the rock shaft 52 which reciprocates the link 55 to move the feed dog forward and back is journaled at its front end in a suitable bearing in the depending web or bracket 20 and at its rear end in a bracket 57 depending from the under surface of the work support preferably near the edge thereof. The shaft 52 is surrounded by and supports a sleeve shaft 58 which is provided at its forward end with an upwardly extending arm 59 to the end of which is secured the link 32 which actuates the rock shaft 29 to raise and lower the feed dog and work support. The sleeve shaft 58 is provided at its rear end with a similar arm 60 which is pivotally connected at its end to a link 61 which has at its opposite end a strap 62 embracing an eccentric 63 on the main shaft of the machine. The rock shaft 52 is oscillated through an arm 64 extending laterally from its rear end which is connected to a floating link 65 which at its upper end is provided with a yoke 66 which embraces a cam 67 upon the main shaft of the machine.

The length of feed is controlled by the extent of longitudinal movement of the floating link 65. The floating link 65 is

connected by a link 68 to a stud 69 in the end of one arm 70 of a bell crank lever which is pivoted upon a stud or screw 71 extending inwardly from the vertical wall of the standard 2. The other arm 70 72 of the bell crank lever is provided with a thumb screw 73 having a shank 74 extending through an arcuate slot 75 whereby the bell crank lever may be adjusted about its pivot 71. When the bell crank lever is so adjusted that the stud 69 which connects the lever 68 and the arm 70 is in the plane of the axis of the link 65. The vibration of the yoke 66 with the cam 67 will not cause any vertical movement 80 of the floating link 65 but will merely oscillate the same. If, however the bell crank lever be so adjusted that the pivotal stud 69 lies at one side of the axial plane of the floating link 65 the oscillation of the yoke will cause a longitudinal movement of the floating link as well as an oscillation thereof. This longitudinal movement of the link 65 will serve to oscillate the arm 64 of the rock shaft thereby transmitting an 90 oscillating movement to the arm 53 which reciprocates the link 55 to move the dog longitudinally, and the amount of reciprocation thus transmitted to the dog may be very accurately controlled by the adjustment of the bell crank lever 70—72 above described.

As heretofore stated the means for operating the feeding mechanism is compact in form and provides ample space beneath the bed plate of the machine for the introduction of the bender mechanism and the parts for operating the same. While the bender mechanism has no special relation to the present invention it may be stated as disclosed herein that it comprises a bender 76 journaled in suitable bearings in bosses extending laterally from the web or bracket 20, the upper end of the bender extending through the base plate to present a bent up or crimped portion of the goods in the path of the needle. The bender 76 is attached to a telescoping arm 77 which enters an arm 78 extending laterally from the shaft 79 which is mounted in suitable bearings 80—81 depending from the bed plate of the machine at the opposite side thereof from the side which supports the feeding operating shafts.

The bender shaft 79 is provided at its opposite end with an arm 82 which is yieldably connected by a yoke 83 and spring 84 to a rod 85 depending from a link 86 which has at its upper end a yoke 87 embracing a cam 88 upon the countershaft 89, the yoke 87 being maintained in proper relation to the cam by a link 90 connected to said yoke and to a stud 91 secured to the wall of the standard 2. In operation the rotation of the countershaft 89 through the gear 92 which meshes with a gear 93 on the 130

main shaft causes the reciprocation of the link 86 which in turn actuates the rock shaft 79 to raise and lower the bender in synchronism with the oscillation of the needle.

5 As illustrated herein the ratio of the gears 93, 92 is that of two to one and inasmuch as the needle oscillates once upon each revolution of the main shaft the bender is thrust upwardly upon every second revolution of 10 the main shaft.

Suitable means may be provided to raise and lower the work support in order to provide for the introduction of the material between the work support and the presser foot.

15 As illustrated herein the lower end of the work supporting standard 19 is provided with a laterally extending flange or ledge 93 which may be engaged by the end of the lever 94 pivotally mounted upon a stud

20 95 in a suitable boss 96 extending upward from the under surface of the bed plate, the opposite end of the lever 94 being provided with a boss 97 adapted to receive a knee lever or handle. It will be obvious that by 25 pressing laterally upon the boss 97 the lever 94 may be rocked to depress the work support in the usual manner.

Having thus described my invention what I claim as new and desire to secure by Letters Patent is:

30 1. In a sewing machine having a yieldable work support, stitch forming mechanism and a presser foot located above said work support; a feed dog, a rock shaft mounted in said work support and means connecting said rock shaft to said work support operable upon the oscillation of said rock shaft to move said support and said dog alternately in coöperative relation with said presser foot 35 and means for imparting forward and backward movement to said feed dog.

40 2. In a sewing machine having a yieldable work support and stitch forming mechanism and a presser foot located above said work support; a feed dog, a rock shaft mounted in said work support and having an arm pivotally and slidably connected to said feed dog adapted upon actuation of said rock shaft alternately to move said support and dog into coöperative relation with 45 said presser foot and means for imparting forward and backward movement to said feed dog.

45 3. In a sewing machine having a yieldable work support, a stitch forming mechanism, and a presser foot located above the same; a feed dog, means for pivotally connecting said work support and feed dog operable to move said support and dog alternately into 50 coöperative relation to said presser foot, an adjustable yieldable means independently supporting the ends of said feed dog whereby the pressure of the heel and toe of the said dog may be regulated.

55 4. A sewing machine having a bed plate, a

work support yieldably supported therefrom and stitch forming mechanism located above said work support, lugs projecting downwardly from the said bed plate, sliding members yieldably mounted in said lugs, a 70 feed dog, means connecting said feed dog to said yieldable members to provide for the independent yielding of the ends of said dog, means for imparting a backward and forward movement to said dog and means for causing an upward and downward movement thereof.

5. In a sewing machine having a work support, stitch forming mechanism and a presser foot located above the same; feeding 80 mechanism comprising a feed dog, independently yieldable supporting bearings for the ends of said feed dog, a rock shaft journaled in said work support and provided with an arm slidably engaging said feed dog, means 85 for actuating said rock shaft to cause the feed dog and work support alternately to be raised and lowered in respect to the presser foot, and means for imparting a forward and backward movement to said feed dog. 90

6. In a sewing machine comprising a rigid presser foot, a yieldable work support and stitch forming mechanism in operable relation thereto, feeding mechanism comprising a feed dog, independent means for yieldably 95 supporting the ends of said dog, a rock shaft journaled in said work support and provided with an arm pivotally and slidably engaging said feed dog, means for actuating said rock shaft to raise and lower said dog relatively 100 to the surface of the work support and means for imparting forward and backward movement to said dog.

7. A sewing machine having a bed plate, a work support and stitch forming mechanism, feeding mechanism comprising a feed dog having a downward, laterally slotted extension at each end, yielding members slidably mounted in journals supported by said bed plate, links connecting the ends of said members to said feed dog extensions, pivotally mounted guiding links engaging the slots of said extensions, means for raising and lowering said feed dog and means for imparting a backward and forward movement to the 11 same.

8. In a feeding mechanism for sewing machines, a feed dog, and means for operating the same comprising a rock shaft and connections between said rock shaft and said feed dog to cause backward and forward movement of the latter, a sleeve surrounding said rock shaft, means for oscillating said sleeve and means connecting said sleeve to said feed dog to cause an upward and downward movement of said dog. 11

9. In a sewing machine, a bed plate, stitch forming mechanism, a feed dog, means for operating said feed dog comprising a solid rock shaft supported in bearings depending 11

from said bed plate, means connecting said rock shaft to said feed dog to cause forward and backward movement thereof, a sleeve surrounding said rock shaft, means connecting said sleeve with said feed dog to cause upward and downward movement thereof, and means for actuating said rock shaft and said sleeve.

10. In a sewing machine a bed plate, stitch forming mechanism in operative relation in respect thereto, a feed dog, means for actuating the same comprising a solid rock shaft journaled in bearings beneath the bed plates, means connecting said rock shaft to said feed dog to cause forward and back-

ward movement thereof, means for adjusting the amplitude of oscillation of said rock shaft, a sleeve surrounding said rock shaft and supported thereby, means for oscillating said sleeve and means connecting said sleeve 20 to said feed dog for imparting an up and down movement to said dog.

In testimony whereof, I have signed my name to this specification, in the presence of two subscribing witnesses.
